INVENTOR:

Albert A. Griswold

by Chas. H. Luther
ATTORNEY:

UNITED STATES PATENT OFFICE.

ALBERT ABBE GRISWOLD, OF PROVIDENCE, RHODE ISLAND, ASSIGNOR OF ONE-HALF
TO JOHN FRANCIS CHEVALIER, OF BROOKLINE, MASSACHUSETTS.

FLEXIBLE SHINGLE.

1,427,154.

Specification of Letters Patent. Patented Aug. 29, 1922.

Application filed February 14, 1921. Serial No. 444,970.

To all whom it may concern:

Be it known that I, ALBERT ABBE GRISWOLD, a citizen of the United States, residing at Providence, in the county of Providence and State of Rhode Island, have invented a new and useful Improvement in Flexible Shingles, of which the following is a specification.

My invention has reference to an improvement in flexible shingles and more particularly to an improvement in flexible shingles adapted to be laid diagonally.

In the construction of roofs and the like on which flexible shingles are laid diagonally, it is necessary to hold down the free or lower corner of the shingles so as to prevent bending or curling up of the free end of the shingles and allowing rain, snow or sleet to beat up under the shingles, thereby giving an unsightly appearance and causing the roof to leak.

The object of my invention is to improve the construction of such a flexible shingle, whereby the means for holding down the free or lower corner of the shingle is formed integral with the shingle.

My invention consists in the peculiar and novel construction of such a flexible shingle, said shingle having twin oppositely disposed means formed integral with the shingle, for holding down the lower corner of the shingle, thereby eliminating auxiliary means heretofore used for this purpose.

Figure 1 is a plan view of a portion of a flexible shingled roof, said flexible shingles being provided with my improved twin oppositely disposed means formed integral with the shingles, for securing the outer or lower corner of the shingles in place on the roof.

Figure 2 is a plan view of my improved flexible shingle.

Figure 3 is an inverted plan view of my improved flexible shingle.

Figure 4 is a detail vertical edge view of the fastening end of the shingle, and

Figure 5 is an enlarged transverse sectional view taken on line 5, 5 of Figure 3.

In the drawing 6 indicates the sheathing of a roof and 7, 7 my improved flexible shingles. The roof sheathing 6 may also represent the sheathing on the walls of a building. The flexible shingles 7, 7 may be constructed of any suitable flexible material. Each shingle 7 has, before the bent un-

der twin oppositely disposed flaps are formed, a lower corner 8 which is split centrally upwards at 9 a predetermined distance, on a line with the upper corner of the shingle, as indicated in dotted lines in Figure 3. The twin corners thus formed are then bent under into twin oppositely disposed fastening flaps 10, 10 parallel with and spaced from the body of the shingle the thickness of a shingle. Each fastening flap 10 has a pointed end 11 and the flaps are folded under in such a way as to form an opening 12 in the bottom edge of the shingle. The sides 13, 13 of the opening 12 are approximately parallel with the lower sides or edges of two shingles previously laid, as shown in Figure 1. The pointed ends 11, 11 of the fastening flaps 10, 10 extend out sidewise slightly beyond the edges of the shingle, as shown in Figures 2 and 3, so that they can be easily seen, and this aids in the laying of the shingles. The distance shown in the drawing between the pointed ends 11, 11 and the edges of the shingle is exaggerated to more clearly show my invention.

In shingling a roof or the like with my improved flexible shingles 7, 7 the shingles are laid diagonally. Each course is laid by placing a shingle 7 of the next upper course over a shingle 7 of the next lower course in a position for the pointed ends 11, 11 of the fastening flaps 10, 10 to go under the edges of two adjacent lower shingles. The shingle is then moved upwards and the twin fastening flaps 10, 10 forced under the adjacent edges of two shingles in the lower course, as shown in Figure 1, thereby interlocking, holding down and securing the lower end of the shingle to two shingles previously nailed to the roof, in the lower course. Only two nails 14, 14 are used for each shingle and the nails are nailed through the shingles adjacent the side corners of the shingles, as shown in Figure 1.

By this construction the twin fastening flaps for holding down the lower corner of the shingle are formed integral with the shingle, thereby eliminating any auxiliary means heretofore used and the shingles are laid in position for nailing in one operation.

I do not wish to confine myself to the construction or shape of the twin bent under fastening flaps 10, 10 as the shape or contour of these flaps could be varied, the object

being to so shape and position each twin flap relative to the shingle, that the ends of the flaps will protrude beyond the edges of the shingle and that the flaps will easily 5 go under the edges of two adjacent shingles, previously laid, as described.

Having thus described my invention I claim as new:—

1. A flexible shingle having two oppositely disposed turned under fastening flaps with ends which protrude beyond the edges 10 of the shingle, said fastening flaps being adapted to go under the edges of shingles previously laid, for the purpose as described.

2. A flexible shingle having two oppositely disposed turned under fastening flaps with pointed ends which protrude beyond 15 the lower edges of the shingle, said fastening flaps being adapted to go under the adjacent edges of two shingles previously laid, for the purpose as described.

3. A flexible shingle having an angular notch in its lower end, the sides of said notch being approximately at right angles 25 to each other, a turned under fastening flap extending from each angular edge of the notch, each fastening flap having an end which extends beyond the lower sides of the shingle, said fastening flaps being 30 adapted to go under the adjacent edges of shingles previously laid, for the purpose as described.

4. A flexible shingle having two turned under fastening flaps with ends in oppositely disposed relation, said ends being 35 adapted to go under the adjacent edges of two shingles previously laid, there being a space between the turned under flaps, for the purpose as described.

In testimony whereof, I have signed my name to this specification.

ALBERT ABBE GRISWOLD.
